GARBAGE CAN DOLLY

David B. Maris, 4601 N. 68th St., No. 142,
Scottsdale, Ariz. 85251

Filed Sept. 6, 1968, Ser. No. 13,426

Term of patent 7 years

Int. Cl. D12—02

U.S. Cl. D14—3

The single feature of the drawing represents a perspective view of a garbage can dolly showing my new design.

The opposite sides are mirror images of the sides shown.

I claim:

The ornamental design for a garbage can dolly, substantially as shown and described.
